UNITED STATES PATENT OFFICE

MILLER REESE HUTCHISON, OF WEST ORANGE, NEW JERSEY, ASSIGNOR, BY MESNE ASSIGNMENTS, TO ACOUSTIC PRODUCTS COMPANY, OF NEW YORK, N. Y., A CORPORATION OF DELAWARE

LOUD-SPEAKER

Application filed June 18, 1926. Serial No. 116,854.

This invention relates to further improvements in acoustic apparatus as embodied in sound reproducing instruments or loud speakers and has for one of its objects, by a novel combination of parts and principles, to produce superior results in radio reception throughout the musical scale.

It is also an object of my invention to construct a scientific, and at the same time a compact instrument of superior power as to intensity and volume of sound without distortion, and to project sound with increased clearness and truth.

With the above and certain other objects in view which will become apparent as the description proceeds, my invention consists in the novel parts and combination of parts, all as hereinafter will be more fully described and particularly pointed out in the claims.

In a copending patent application, Serial Number 87,073, filed February 9, 1926, loud speakers, and in another copending patent application, Serial Number 98,763, filed March 20, 1926, loud speakers, and in still another patent application, Serial Number 112,034, filed May 27, 1926, loud speakers, I have set forth specifications, drawings and claims covering different designs and principles of loud speakers more or less pertinent to my present invention.

Referring to the accompanying drawings forming a part of this specification in which like numerals designate like parts in all the views:

Figure I is a side view of one design of one of my instruments, partly in section and partly in elevation.

Figure II is a one-half front elevational view of one design of one of my instruments, being particularly the one-half front view of Figure I or of Figure III.

Figure III is a side elevational view of one design of one of my instruments with a somewhat different distribution of parts over the design shown in Figure I.

Figure IV is a side view partly in section and partly in elevation of another design of one of my instruments.

Figure VI is a side view in partial cross section and partial elevation of a modifica-

tion of the instrument shown in Figure IV.

Figure V is a diagrammatic view partly in section and partly in elevation of a modification of Figure I.

With further reference to Figure I, 10 is an electromagnetic diaphragm telephone receiver system of standard design with short lengths of protruding coiled connecting wires. Since I have illustrated and fully described this type of electro-magnetic diaphragm receiver in my previous patent applications, and since it comprises the well-known parts of permanent steel magnets, soft iron pole pieces, insulated wire windings, diaphragm rings or washers, and so forth, it is not deemed necessary to illustrate it further here. This standard telephone unit is provided with an open throatway shown exteriorly at 11, leading from the diaphragm to the hole or opening 12, in the back plate member 13. 14 is a like electro-magnetic diaphragm telephone receiver system, but it has in the place of an open throatway, a small guideway 15 for the reception of the light wire rod piston 16 one end of which joins or touches the diaphragm of the telephone receiver unit (diaphragm not shown) and the other end terminating in screw threads (also too small to be shown) in the discs or buttons 17.

These discs or buttons not only act to hold securely the membrane or material of the cone sound projector member 18, but serve as tuning weights, since I may use heavy or light discs or buttons, according to adjustment and characteristics of resonance required, or I may use a series of light discs or buttons screwed on successively to increase the mass which must be set in vibratory motion by the wire piston 16, in contact with the diaphragm. The back plate member 13, supporting the telephone unit 10, terminates in the flare shown at 19—19. The front plate 20, supporting the telephone unit 14, terminates in the flare 21, 21, 20, 20, furthermore supports the small conical sound deflector 26 opposite the opening 12 in the back plate member 13 and serves to deflect the sound waves from the telephone unit 10 towards the flares 19, 19, and 21, 21, and 21, 21, embrace and confine air in the space 22. A wooden ring mem-

ber 23 supports the outer edge or periphery of the fibre parchment or membrane of the cone 18.

With further reference to Figure II which shows a left hand portion of a front view of Figure I as well as a front view of Figure III, 17 are the discs or buttons at the apex of the conical membrane 18 held at its periphery by the wooden ring 23, and 19, 19, and 21, 21, are the flares of the air confining plates shown and described in the previous figure.

When I speak of air confining, I means it in the sense that air is confined in a horn, flute, organ pipe or other musical instrument.

With further reference to Figure III, the end of the wire piston is shown at 16, the weighting discs or buttons at 17 at the apex of the parchment cone 18 actuated by the telephone receiver unit shown in dotted lines at 14. The back plate 13 is here shown in elevation mounting the telephone receiver unit 10 at a position eccentric to the middle or apex of the cone 18. The diaphragm of this unit 10 communicates its vibrations to the confined air 22, at the indicated eccentric or off center position from the member 13, and also eccentric or off center from the apex of the cone member 18.

With further reference to Figure IV, 13 is the back plate member. 14, 14, are a pair of telephone receiver units equipped with the guideways 15, 15, such as I employ in Figures I, II and III on the cone members. The wire pistons 16, 16, and the discs or buttons 17, 17, attached to the cones 18, 18, which are in the present design centrally located and mutually opposed, and supported at the wooden rings 23, 23, and 24, 24, and furthermore the wooden discs 27, 27, support the telephone units 14, 14. Here I secure the double and powerful effect of two electromagnetic diaphragm systems actuating two mutually opposed cone loud speaker projectors, delivering vibrations of the confined air 22 against the curved reflector member 25, 25.

With further reference to Figure VI, I again show a somewhat like construction with the telephone receivers at 14, 14, and the two mutually opposed cones 18, 18, but the cone at the right hand side of the diagram is of smaller diameter than the cone at the left hand side of the diagram, and therefore will have a totally different resonance period, or musical note, over the cone at the left hand side of the disc and will communicate vibrations to the confined air 22 and be deflected by the curved member 25.

With further reference to Figure V, I am showing a modification over Figure I, and this modification is in effect a diagram of Figure I, but with the cone member 18 unsupported at its periphery. These illustrations it must be understood are more in the nature of diagrams setting forth the mutual co-operating

essential principle of my instruments than actual working drawings. I have preferred to illustrate my invention in this diagrammatic way in the interest of clearness leaving minor details in the matter of giving support to certain co-operating members of the design to the skill and art of the manufacturer.

Although I have shown a number of combinations of telephone receivers, confined air masses (confined in the sense that air for resonating purposes in confined in other musical instruments) and cone members, I do not wish it to be understood that I am restricted to these precise combinations because the principles underlying the mutual action of my confined air masses and cone and disc sound projectors are accompanied by new and surprising results, and I am claiming broadly the associations of these fundamentals. Furthermore, I do not confine myself to telephone receivers as sound emitting devices, since I may use other devices or systems, such, for example, as musical arcs or speaking arcs, or apparatus without diaphragms, without departing from the spirit of my invention.

With the combination or association of a pancake, or deep pie shaped mass of air, a sound emitting device therefore, and a cone loud speaker element with a sound emitting device therefore, I secure new and superior results. I also secure greater power or volume in my sound projection because I employ two sound emitting devices connected to the source of sound producing energy. I may connect my sound emitting devices, whether they be telephone receivers, or musical or speaking arcs in series or in parallel.

In the design shown in Figure I, I secure unusual results when the cone speaker element is weighted or adjusted for bass notes, and the confined air between the plate members has different characteristics as to resonance. I am, therefore, with this design and construction enabled to cover a very wide range of what I may term the musical spectrum. I am not so successful however, with instruments of small disc construction because the column of air is so short for each hypothetical "horn" in the pancake design that only high pitched notes, such as piccolo, high notes of violin etc. are properly reproduced. I desire however, to point out that the fullness of performance is only a matter of dimensions, and that with large disc instruments I secure best results. For small discs and small pancake masses of air, I get better results when I actually construct partitions, apportioning resonating masses of air of increasing lengths, but I desire to cover fundamentally the several phases of my invention, and be not restricted to the hypothetical "horns" since I may actually lay them off between my discs with partitions.

When I say pie-shaped mass of air, I should point out that segments or pie shaped masses which may be laid off by lines or actual partitions, drawn or laid from the eccentrically positioned opening, to the periphery, are modified at the periphery over true pie-shaped masses because of the flare due to the horn shaped reflector periphery of the two plates. However, I secure pie-shaped, or wedge shaped masses of confined air with flares, the links of the pie-shaped or wedge shaped masses of air which may be portioned off having obviously now various lengths.

By selecting various weights, 17, for my piston wires actuating the cones 18, I am enabled to secure the baspest notes on the musical scale, clear and strong without conflict or interference with the series of higher notes, tones and overtones which emanate from my pan cake masses of resonating confined air between the associated discs of plates. It would be inconvenient, if not impossible, to secure the results obtained by either the cone alone or the resonating pie-shaped masses of confined air, unless each member was constructed upon a prohibitive scale.

To secure the bass notes from a pie-shaped mass of air which are forthcoming from my weighted cone, I would have to utilize air confining discs or plates of great diameter to secure columns of air long enough to resonate at the baspest notes. Upon analysis and study of my instrument with combination of cone and confined air segments, it now becomes apparent how I secure the wide range of notes, tones and overtones without interference, and by virtue of a duplex sound emitting it can be appreciated how I am also enabled to secure great power and volume of sound, accompanied by scientific truth of sound.

Having described my invention, I claim:—

1. A loud speaker comprising a pair of plates with an air space between, horn-like flares at the peripheries of the plates, an opening eccentric to the center in one of the plates, a sound emitting device in communication with said opening, and a second sound emitting device in communication with the apex of a cone sounding member.

2. A loud speaker comprising a pair of plates with an air space between, horn-like flares at the peripheries of the plates, an opening eccentric to the center in one of the plates, a sound emitting device in communication with said opening, a sound deflector substantially opposite the said opening, and a second sound emitting device in communication with the apex of a cone sounding member.

60 Signed at New York in the county of New York and State of New York, this 8th day of June, A. D., 1926.

MILLER REESE HUTCHISON.
